FIG. 1 is a front elevational view of a disc player showing my new design;
FIG. 2 is a top plan view thereof;
FIG. 3 is a bottom plan view thereof;

FIG. 4 is a front elevational view of an another embodiment;
FIG. 5 is a top plan view thereof; and,
FIG. 6 is a bottom plan view thereof.

The even broken line showings of an optical disc player in FIGS. 1-6 are for illustrative purpose only and form no part of the claimed design. The dot-dash broken lines in FIGS. 4-6 define, but are not included in, the boundaries of the claimed design.
